CLAIM

The ornamental design for a handset rear cover, as shown and described.

DESCRIPTION

FIG. 1 is a perspective view of a handset rear cover showing our new design;

FIG. 2 is a front view thereof;

FIG. 3 is a right side view thereof;

FIG. 4 is a left side view thereof;

FIG. 5 is a top view thereof;

FIG. 6 is a bottom view thereof; and,

FIG. 7 is a rear view thereof.

The broken lines immediately adjacent the shaded surfaces represent boundaries of the claimed design. All other broken lines depict unclaimed environment. The broken lines form no part of the claimed design.
